CLAIM

We claim the ornamental design for a toothbrush handle, as shown and described.

DESCRIPTION

FIG. 1 is a front isometric view of a toothbrush handle with a toothbrush head shown for environment.

FIG. 2 is a front isometric view of the toothbrush handle of FIG. 1.

FIG. 3 is a front elevation view of the toothbrush handle of FIG. 2.

FIG. 4 is a rear elevation view of the toothbrush handle of FIG. 2.

FIG. 5 is a right side elevation view of the toothbrush handle of FIG. 2.

FIG. 6 is a left side elevation view of the toothbrush handle of FIG. 2.

FIG. 7 is a top plan view of the toothbrush handle of FIG. 2; and,

FIG. 8 is a bottom plan view of the toothbrush handle of FIG. 2.

The dash-dot-dash type broken lines define the boundaries of the claimed design. The dash-dash-dash broken lines shown in the figures are included for the purpose of illustrating portions of the toothbrush handle and form no part of the claimed design. Additional broken lines shown in FIG. 1 are for purposes of illustrating environment only and form no part of the claimed design.
